COMBINATION PARK BENCH AND PLANTER

Robert S. Wormser, Hillsdale, Mich., assignor to Game-Time, Inc., Litchfield, Mich., a corporation of Michigan

Filed Mar. 4, 1968, Ser. No. 10,845

Term of patent 14 years

Int. Cl. D6—01

U.S. Cl. D15—11

FIG. 1

FIG. 2

FIG. 4

FIG. 1 is a perspective front view of a combination park bench and planter in accord with my new design,

FIG. 2 is an end elevational view of one end of the combination park bench and planter, the other end being identical thereto,

FIG. 3 is a top plan view, and

FIG. 4 is a bottom view of my new design.

I claim:

The ornamental design of a combination park bench and planter, substantially as shown and described.
